UNITED STATES PATENT OFFICE.

CHAUNCEY F. THATCHER, OF BROOKLYN, NEW YORK.

MEANS FOR ATTACHING HEELS.

Substitute for application Serial No. 236,784, filed May 27, 1918. Renewed December 20, 1921, Serial No. 523,771. This application filed June 20, 1926. Serial No. 119,635.

My invention relates to means for attaching heels and while it is applicable to men's and women's shoes, I have shown in the drawing herein the invention applied to 5 women's footwear.

The invention relates more particularly to the heel of a shoe or oxford tie and to the means for securing the heel to the footwear. The object of my invention is to simplify 10 the method of attaching the heel for the purpose of reducing the cost of manufacture of the footwear. By using the present invention manufacturers may eliminate much of the hand labor heretofore employed in 15 applying heels to footwear and the time required to permanently attach the heels may be considerably reduced so that much less space is required where footwear is manufactured in large quantities. Another object is to provide a strong and permanent 20 attachment between the heel and footwear. In present practice it is common to form the heel and to attach it to the shoe by gluing it or by gluing and nailing it. When the 25 glued heel is attached in place it is necessary to apply a screw clamp to hold the heel tightly on the shoe and it is necessary to leave the screw clamp on the shoe until the glue has thoroughly hardened. It is customary 30 to place the shoes with the attached screw clamps in racks for a day or more to allow the glue to harden before the clamp is finally removed; and this makes it necessary to provide considerable rack space.

35 It requires time and careful handling in order to set the heel and to apply the screw clamp in place.

The present invention avoids the difficulties above set forth. I provide a simple 40 device for drawing the heel against the shoe and for holding it in place sufficiently tight so that the usual screw clamp need not be used, and the holding device becomes a permanent part of the shoe, rendering the connection 45 between the heel and shoe very strong. The attaching or holding means is very simple and inexpensive and it is very easy to apply.

In the drawing forming part of this application,

Figure 1 is a side elevation with parts broken away showing a shoe embodying my invention,

Figure 2 is a sectional view thereof taken 55 on the line 2-2 of Figure 1.

Figure 3 is an inverted plan view of the heel detached, parts being broken away,

Figure 4 is a rear elevation of the shoe with parts broken away, and

Figure 5 is a perspective view of the locking member.

I have shown an ordinary woman's shoe 1 having a popular shape heel 2 attached thereto. It is to be understood that the shape or style of the shoe and heel may be varied 65 in any manner and that the present invention is applicable to men's or women's shoes or ties, or, in fact, to any form of footwear which includes a heel. The term shoe is used herein to include any form of footwear 70 which has a heel.

The present invention may be utilized for shoes having heels made entirely of leather, or which are made of wood or composition, whether or not the wood or composition is 75 covered with a leather covering. In the drawing I have shown a wooden heel having a leather covering 3, 4 and with a top lift 5 of leather. The shoe when prepared for the attachment of the heel generally has a 80 rounded or curved seat 6 shaped by trimming the leather as shown so that the seat 6 is convex, the edging 7 being turned in and secured by gluing. Under former methods the heel is glued directly to the seat 6 and a screw clamp is then applied to hold the heel tightly against this seat and the shoe is 85 then laid upon a rack for a day or more to allow the glue to set and harden.

In the present case I apply to the seat by 90 a mechanical and preferably permanent connection, a rigid member for drawing down the heel against the seat and for holding it there, and this member becomes a permanent part of the shoe. The member 8 for this purpose shown herein comprises a wedge which may be stamped or drawn from sheet metal. It consists of a top plate 9 adapted to lie in a plane inclined in relation to the heel seat; of side walls 10, and an end wall 11. The 100 side walls converge from their line of junction with the top plate and their bottom edges 12 are inclined in relation to the top plate 9. This makes the sides tapered in shape, being deeper at the back and running down 105 to the point 13.

The rear wall 11 is inclined in relation to the top plate 9 and as it meets edge to edge with the sides 10 it has a tapered outline.

There are nail holes 14 in the top plate 9 110

the shoe by glue alone. It is to be understood that the locking device is a permanent part of the product.

It is not necessary that the locking members be made hollow and of metal but I prefer to thus make them because they can be made in this manner very uniformly and very cheaply and at the same time they are comparatively stronger.

10 This is a substitute of the application Serial No. 523,771 filed Dec. 20, 1921 the latter being a renewal of application Serial No. 236,784, filed May 27, 1918.

Having described my invention what I 15 claim is:

1. An article of footwear having a heel seat, a locking member thereon of graduated height and having sides inclined horizontally in relation to the heel seat, and a heel 20 having a recess having an open end and un-

dercut side walls, adapted to receive said locking member in locking engagement therewith, whereby as the heel is moved along the heel seat it will be forced by said locking member against said seat. 25

2. An article of footwear having a heel seat, a locking member thereon tapering in height and comprising a top plate 9 inclined horizontally in relation to the heel seat and having inwardly inclined and converging 30 sides 10 and end 11, and a heel having a recess having an open end and undercut side and end walls, said recess being adapted to receive said locking member endwise therein, whereby the locking member and heel will 35 have a dovetail and wedging connection.

Signed at the city, county, and State of New York this 3rd day of May, 1926.

CHAUNCEY F. THATCHER.
